UNITED STATES PATENT OFFICE.

JOSEPH H. JACOBS, OF ATCHISON, KANSAS.

ILLUMINATED FLYING TARGET.

SPECIFICATION forming part of Letters Patent No. 393,435, dated November 27, 1888.

Application filed January 31, 1888. Serial No. 262,509. (No model.)

To all whom it may concern:

Be it known that I, JOSEPH H. JACOBS, of Atchison, Atchison county, Kansas, have invented a new and Improved Illuminated Flying Target, of which the following is a full, clear, and exact description, reference being had to the accompanying drawings, forming a part hereof.

My invention relates to flying targets; and it may be said to consist in the devices and the peculiar construction, combination, and arrangement of devices hereinafter set forth, and pointed out in the claims, the object being to produce a target for all-around use, either in day-time or after darkness sets in.

In the drawings, which illustrate the manner of carrying out my invention, Figure 1 is a perspective view of the improved target devoid of all illuminating attachments. Fig. 2 is a perspective view of the carrier in which the target is placed to be thrown from the trap. Fig. 3 is a plan of a target located in the carrier. Fig. 4 is an elevation in section, the section being taken on line $x x$, Fig. 3, and 25 the different illuminating devices being in position. Fig. 5 is a detail view in perspective of the attachment used in illuminating the under side of the target. Fig. 6 is a detail section showing a portion of the shell, the section being taken on line 2 2, Fig. 3; and Fig. 7 is a detail view of a device used to illuminate the upper side of the target.

A indicates the target, which is to be made circular in plan and of an inverted-dish shape 35 in elevation. At the center of the target is a flat disk, B, that is depressed or sunken below the surface of the contiguous wall of the target, leaving substantially square offsets or ledges a , as shown.

The body of the target is made thicker at the periphery and of course thinner as it recedes therefrom. At the periphery the surface is made substantially at right angles to the plane of the target, and the interior of this 45 surface is traversed by groove 3, and a corresponding annular rib, 7, is located on the exterior of this surface directly opposite said groove. An annular groove, 9, is formed in the body some distance above the rib 7, and 50 short transverse grooves 12 are located radially in the body of the target. These latter are shown more clearly in Figs. 3 and 4, while in

Fig. 1 a variation of construction is shown, the grooves 12 being supplanted by ribs 13, which construction is obviously just the reverse of that shown in Figs. 3 and 4. 55

In Fig. 1 all that has been done is to locate the short ribs 13 on the exterior surface of the body instead of on the inside thereof. This change will be better explained by referring 60 to Fig. 6. The body of the target may be made of any suitable brittle material; but, preferably, it is composed of some of the different solid coal-tar products or pitchy substances, which can be molded or pressed in 65 forms to proper shape.

The comparatively heavy rim of the target acts as a balance-ring, and the interior groove, 3, is adapted to hold the lower illuminating attachment, 2.

The target is readily broken when a shot strikes any part thereof. The target may be illuminated by means of different forms of devices attached thereto in any preferred manner. Some of my preferred devices I will now 75 proceed to describe.

For illuminating the upper side of the target, I secure two or more fuses or fusees, 4, to a rubber band, 8, by means of a short wire connection, 10, which latter separates the fuse and 80 the rubber, preventing destruction of the latter by burning. I then stretch said rubber band around the body of the target in the groove 9, as clearly shown in Fig. 3; or I stretch said rubber band directly across the upper side 85 of the target, as indicated by dotted lines in said figure. In the latter case said rubber band is attached to the target by means of oppositely-located lugs b , which are cast in position, said rubber band being hooked thereover 90 during use. It is obvious that said lugs b can either be formed integral with the body of the target, of the same material, or they can be supplanted by metallic pins secured in position in any desired manner. 95

For illuminating the under side of the target, I provide a removable or detachable plate or piece of pasteboard or wood, 2, of suitable length to extend across the interior of the target and having its respective ends sprung into 100 the groove 3, and secure suitable fuses, 4, to the under side of this detachable plate by means of wires 10, as shown.

It is evident that other styles of illuminat-

ing devices can be used, and that numerous slight changes in the manner of securing these devices to the target could be resorted to without departing from the scope and spirit of my 5 invention; hence I wish it understood that I do not confine myself to the precise construction herein shown, but consider myself entitled to all such variations as come within the scope of my invention.

10 The devices for illuminating the upper side of the target can be used alone, and the devices for illuminating the under side can also be used without any connection whatever with those on the upper side, and vice versa. Another 15 illuminating device is in the form of a fuse or fusee, 5, which is located in an aperture, such as 6, formed in the disk B and projecting upwardly as great a distance as may be desired. A number of these can be used, if so desired, 20 by providing suitable apertures. Of course this latter arrangement is not to be used when the rubber cord 8 is stretched across the target, as, if it were, said cord would be burned and destroyed before the target has been shot at. It will be observed that the central device, 5, is sunken, so that it cannot be struck by a shot. This, however, depends upon its 25 length. The fuse or fusees can be made of paper, linen, cotton, or other suitable material, 30 saturated with a solution of saltpeter, and can be readily ignited by merely touching with a live coal or lighted cigar, or in any desired manner, before or after they have been put in the trap. A fuse or illuminating device thus 35 constructed will not be extinguished easily, but will show up in a very pretty way when flying through the air, and as the target revolves rapidly it will show a perfect circle of sparkling fire, and thus afford a splendid target to shoot 40 at, and indicate plainly when hit by shot, as the circle will be broken and sparks of fire will scatter in all directions. A fuse prepared in this way with a solution of saltpeter will be 45 perfectly safe in handling, and when ignited will burn comparatively slowly.

The length of the different fuses can be regulated by cutting off according to whether the target is to make a long or short flight.

The fuses can be prepared so that they will 50 throw off fires of different colors, if so desired, thereby presenting a more gorgeous spectacle than they otherwise would.

The different fuses arranged around the body 55 of the target, as before described, can be located in openings similar to the way in which the fuse 5 is located, although the rubber cord is much to be preferred for this purpose, as it will separate from the target when the latter breaks and indicate a hit more plainly. (Being lighter, it will not fall to the ground as fast as the broken pieces will.)

I have not deemed it necessary to show a complete trap for flying this target, as no part

thereof except the carrier relates to my present invention.

The carrier C is composed of a Y-shaped metallic frame, which is provided at rear with a lug, e, for attaching it to the arm of the trap. The target is to be placed upon the upper side of the frame, and is held in place by means of 70 stop h and a pair of flexible arms, d, which completely encircle the edge of the carrier and prevent its discharge until the proper time arrives. The lower ends of said arms are firmly secured to the Y-shaped frame, and their 75 free ends may be sprung outwardly when the target is inserted. Said yielding arms are located opposite each other, and they each carry near their outer ends a vertical standard, f, which is firmly secured thereto, and projections f', carried by said standards, also help to hold the target in position and keep it from flying upwardly out of the carrier. One of the flexible arms D has its free end extended a considerable distance, and to the outer end of 80 the other is hinged or pivoted a bar, E, which latter is curved to correspond with the curvature of the edge of the target. The free end of said bar is provided with an aperture, t, which is to be engaged by the end i of the 85 opposite arm when holding a target in the carrier.

The operation of this arrangement is as follows: In flying a target the outward pressure of same on hinged bar E will be sufficient to 90 disconnect it from the end i of the spring-arm, and the target will be discharged from the carrier and will begin its flight in the usual way. These operations are best illustrated in Figs. 2 and 3.

Having thus described my invention, what I claim is—

1. A flying target provided with illuminating devices detachably secured thereto by means of an encircling elastic band, so that 105 when the target is broken they will be separated therefrom, substantially as described.

2. A flying target consisting, essentially, of a rim having a groove, a concavo-convex body, and an illuminating device detachable therefrom, which is held in position by an elastic band in engagement with said groove, substantially as set forth.

3. A flying target consisting, essentially, of a rim, a concavo-convex body, an illuminating 115 device detachable therefrom, a central disk, and an annular groove formed in the outer surface of the body and located some distance above said rim to receive an elastic band, for the purpose substantially as set forth.

In testimony whereof I affix my signature in presence of two witnesses.

JOSEPH H. JACOBS.
